UNITED STATES PATENT OFFICE.

DANIEL McCANN, OF CHICAGO, ILLINOIS, ASSIGNOR OF ONE-THIRD TO
F. ROBERT BARTSCH AND ONE-THIRD TO LEMUEL C. HATTON, BOTH
OF CHICAGO, ILLINOIS.

BOOKBINDER.

No. 818,777.

Specification of Letters Patent.

Patented April 24, 1906.

Application filed June 30, 1905. Serial No. 267,809.

To all whom it may concern:

Be it known that I, DANIEL McCANN, a citizen of the United States, and a resident of Chicago, county of Cook, and State of Illinois, have invented certain new and useful Improvements in Bookbinders, of which the following is a specification and which are illustrated in the accompanying drawings, forming a part thereof.

10 The invention relates to a binder adapted for retaining a number of copies of magazines, sheet-music, or other matter together in book form, so that they may be conveniently accessible and be protected from wear.

15 The object of the invention is to provide an efficient and durable covering in which book-sections may be neatly and permanently bound by the ordinary user.

The invention consists in the structure to 20 be hereinafter described and claimed and which is illustrated in the accompanying drawings, in which—

Figure 1 is a plan view of my improved binding device, showing the covers open. 25 Figs. 2 and 3 are sectional views on the lines 2 2 and 3 3, respectively, of Fig 1; and Fig. 4 is similar to Fig. 1, but showing a modified construction.

As a support for the binding means there 30 is provided a rectangular frame 10, preferably formed of stout metal wire and slightly longer than the height of the articles to be bound. This frame is adapted to be secured in any convenient manner to the inner face of the 35 back member 11 of an ordinary book-covering 12. The form of securing means shown in the drawings consists of a plurality of clips or rivets 13 14, each having a shank 15, which grips the material of the book-covering, and 40 an overturned head 16 of hook form, adapted for receiving the wires of the frame 10. A part of these clips, as 14, have a rotative engagement with the material of the covering, a washer 17 being applied at either side thereof 45 of to prevent wear. The heads of such clips may be turned to one side to permit the frame 10 to be raised from the cover either by turning in the hooks of the remaining clips

13 as a hinge or by being entirely disengaged therefrom.

50 The frame 10 is inclosed for a portion of its length by a covering or web 18 of binding material, such as canvas or leather, which preferably is put on as a flattened tube carried by the side members 19 20 of the frame, the opposite folds 21 22 being subsequently brought together within the margins of the frame and made to adhere closely by means of stitching or glue.

55 In using the device the back edge of the article to be bound is applied to the covering 18, when the frame 10 is removed from the book-cover, as previously described, and the article is permanently secured in place by means of stitches or wire passing through its 60 leaves and through the material of the web 18. The frame 10 will be then attached to the book-cover by the use of the cleats 13 14. Additional sheets may be added from time to time in the same manner, and when enough 65 have been bound to provide a thickness equal to the width of the frame 10 a neat and durable volume will have been formed. To aid the user in securing the sheets in proper alignment, the web 18 is ruled with a plurality of 70 parallel lines 23.

75 In the form of construction shown in Fig. 4, the frame 10 is provided with spiral cross members 24 25 to give it a moderate degree of flexibility, so that the back of the finished 80 volume may assume the customary rounded form.

I claim as my invention—

1. In a bookbinder, in combination, a book-cover; a frame removably secured to 85 the cover; and a web carried by the frame and adapted for the attachment of sheets thereto.

2. In a bookbinder, in combination, a book-cover, a binding-frame removably secured to the cover, and a canvas web carried 90 by the frame to which the leaves to be bound may be independently secured.

3. In a bookbinder, in combination, a book-cover, a frame having rigid sides and 95 flexible ends, means for securing the frame to

the back of the cover, and means for attaching to the frame the leaves to be bound.

4. In a bookbinder, in combination, a pair of cover-boards; a back-section uniting the boards; a frame removably secured to the back-section; and a sheet-carrying web carried by the frame.
5. In a bookbinder, in combination, a

book-cover; a frame pivotally secured at one end to the cover; means for securing the frame against pivotal movement; and a sheet-carrying web carried by the frame.

DANIEL McCANN.
